UNITED STATES PATENT OFFICE.

CHARLES E. BONINE, OF PHILADELPHIA, PENNSYLVANIA, ASSIGNOR TO THE ELECTRIC SERVICE SUPPLIES COMPANY, OF PHILADELPHIA, PENNSYLVANIA, A CORPORATION OF NEW JERSEY.

SIGN FOR RAILWAY-CARS.

1,004,978.

Specification of Letters Patent.

Patented Oct. 3, 1911.

Application filed July 19, 1910. Serial No. 572,706.

To all whom it may concern:

Be it known that I, CHARLES E. BONINE, of Philadelphia, in the county of Philadelphia and State of Pennsylvania, have invented certain new and useful Improvements in Signs for Railway-Cars, whereof the following is a specification, reference being had to the accompanying drawings.

My invention relates to new and useful improvements in signs, and more especially that class of signs which are used in connection with railway cars in order to give notice of the prospective stations or streets, although it is obvious from certain aspects of the invention, that the same may be used for other purposes.

The invention has more particular relation to the means for operating an elongated flexible curtain containing a series of names, which curtain may be wound upon one roll and unwound from the other, so that the names may be successively displayed.

An object of the invention is to provide a mechanism for operating the rollers on which the flexible curtain is mounted, which means shall be positive in its action and durable in construction, and wherein either one or the other of the rollers is always in operative connection with the operating means.

The invention consists in certain constructions and in certain parts, improvements and combinations, hereinafter more fully specified.

In the drawings which show by way of illustration one embodiment of my invention, Figure I, is a partial front view, and a partial vertical sectional view of my improved device. Fig. II, is a sectional view on the line II, II, of Fig. I. Fig. III, is a sectional view on the line III, III, of Fig. I. Fig. IV, is a sectional view on the line IV, IV, of Fig. II. Fig. V, is a section on the line V, V, of Fig. II. Fig. VI, is a section on the line VI, VI, of Fig. II.

The receptacle in which my improved operating mechanism is mounted, as herein shown, consists of an elongated box 1, having its faces of substantially rectangular form. At one end of the box is an end plate 2, which is of comparatively heavy metal. At the opposite end of the box is a similar end plate 3, of comparatively heavy metal, which has a flange 4, project-

ing a sufficient distance to form a housing for the operating gears for the supporting rollers.

The end plates 2, and 3, are connected by suitable metal pieces 5, and 6, forming the top and bottom of the casing. The top portion 5, is provided with a downwardly projecting flange 7, at the rear of the casing, and a downwardly projecting portion 8, at the front of the casing. The bottom piece 6, is provided with similar parts 9, and 10.

An angle piece 11, is secured to the top metal piece 5, of the casing, and spaced from the flange 7, so as to form a pocket or recess for a glass plate 12, forming the back of the casing. A similar angle piece 11, is attached to the bottom metal piece 6, and forms a pocket for the bottom edge of the glass plate 12. Angle pieces 11, are also attached to the top and bottom portions of the casing at points adjacent the front thereof, so as to form recesses or pockets for the front glass plate 13.

The projecting members 8, and 10, extend at some distance from the bottom and top portions, so as to partially close the front of the casing. These features form no part of the present invention and are, therefore, not claimed herein.

The flexible curtain or sign 14, is attached at one end to a roller 15, and at its other end to a roller 16. The rollers 15, and 16, are journaled in the end plates 2, and 3. At the right hand end of the casing, as viewed in Fig. I, the rollers project through the casing and carry hubs against which flexible straps 17, bear, in order to form a braking device, which will prevent the rollers from running too freely, which might bring about a loose condition of the flexible curtain. The shaft of roller 15, extends through the end plate 3, and carries a beveled gear wheel 18. This gear 18, meshes in a beveled gear wheel 19, carried by a hub 20, which is freely mounted on a shaft 21. The shaft 21, extends in a vertical direction, and has its axis lying in a plane which coincides with the axes of the rollers 15, and 16. The shaft 21, is mounted in bearings 22, and 23, which are carried by the end plate 3. The upper end of the shaft 21, has a collar 24, attached thereto in any suitable way. The hub 20, is located between the collar 24, and the bearing 22, which prevents endwise movement of the hub on the shaft 21, and holds

the gear wheel 19, in mesh with the gear wheel 18. The roller 16, carries a beveled gear wheel 25, which meshes with a beveled gear wheel 26, also loosely mounted on the shaft 21, and held in mesh with the gear wheel 25, by the bearing 23. The gear wheel 26, carries the hub 27. The shaft 21, may be turned by a hand crank 28.

The shaft 21, is provided with a longitudinal groove or recess 29, (see Fig. II), which extends from a point adjacent the hub 27, to a point adjacent the collar 24. Mounted within the groove or recess 29, is a pawl 30, which is pivoted at 31, to the shaft 21. The hub 20, of the gear wheel 19, is provided with a recess 32, which is formed with a radial shoulder 33, and a spiral shaped curved surface 34, extending from the bottom of the recess 32, to and coinciding with, the inner curved surface of the hub. The hub 27, (see Fig. VI), has a similar recess 35, which has a radial shoulder 36, and a curved surface 37, similar to the surface 34. The curved surface 37, however, is located on the opposite side of the recess from that of the curved surface 34.

The locking pawl 30, is so constructed that when the end 38, which coöperates with the hub 20, is housed within the recess or groove in the operating shaft 21, the opposite end 39, of the pawl 30, which coöperates with the hub 27, is thrown out of the recess or groove in the operating shaft to more or less extent. When the recess 35, is brought opposite the end 38, of the pawl 30, as shown in Fig. VI, said pawl may be moved outward into the recess, and the face of the pawl will engage the shoulder 36, on the hub 27, and if the shaft 21, is rotated in the direction of the arrow, Fig. VI, it will cause the hub 27, and gear 26, to rotate therewith, and thus impart a rotary movement to the roller 16, through the gear 25. When the shaft 21, is rotating in the direction of the arrow in Fig. VI, it is also rotating in the direction of the arrow, as shown in Fig. V, relative to the hub 20. This will cause the upper end 38, of the pawl 30, to move away from the shoulder 33, and the inclined surface 34, will crowd the same back into the recess or groove in the main shaft 21, and said main shaft 21, will rotate freely within the hub 20.

Let us suppose the parts are in the position shown in Figs. V, and VI, and the operating shaft 21, is turned in the opposite direction. The end 39, of the pawl 30, will then be carried along the inclined surface 37, and said end gradually move into the recess or groove in the shaft 21. Inasmuch as the pawl 30, is made in one piece and pivoted at 31, the other end 38, of the pawl will be raised out of the groove or recess in the shaft 21, and will contact with the shoulder 33, formed in the hub 20, and positively

lock the hub 20, to the shaft 21, so it will be rotated thereby, and through the gear 18, positively rotate the roller 15. Of course, as the roller 15, is rotated, the flexible curtain being wound thereon, will cause the roller 16, to be rotated by the unwinding of the curtain therefrom, and through the gear 25, the hub 27, will loosely rotate on the shaft 21, and allow the unwinding of the flexible curtain from the roller 16. It will readily be seen, therefore, that I have provided a mechanism wherein by the simple rotation of the operating shaft in one direction or the other, one roller or the other will be locked to the operating shaft, and caused to rotate therewith.

The flanges 4, of the end plate 3, project sufficiently far to house the operating shaft 21, and a metal plate may be attached to the outer edges of the flanges 4, so as to completely inclose the operating mechanism. The end plates 2, and 3, as clearly shown in Fig. IV, may also be provided with projecting flanges on their inner faces to receive the glass plates 12, and 13.

It is obvious that minor changes in the details of construction may be made, without departing from the spirit of my invention, as set forth in the appended claims.

I claim:—

1. The combination of sign rollers and a flexible sign mounted thereon; of gears mounted on the shafts of said rollers; a driving shaft extending at right angles to the axes of said rollers, and driving gears carried by said driving shaft and engaging respectively the gears carried by the rollers; means for holding the driving shaft from endwise movement, means for rotating said shaft; a pawl extending longitudinally of the driving shaft and coöperating with said driving gears, and means whereby said pawl is caused to engage one of the driving gears when said driving shaft is rotated in one direction and for causing said pawl to engage the other gear when said driving shaft is rotated in the opposite direction.

2. The combination with sign rollers and a flexible sign mounted thereon; of gears mounted upon the shafts of said rollers; driving gears adapted to respectively engage said first mentioned gears; hubs carried by said driving gears and having oppositely disposed clutching recesses formed therein; an operating shaft on which said hubs are freely mounted; a locking pawl pivoted to said operating shaft and having its opposite ends adapted to coöperate with the clutching recesses respectively in the hubs of the driving gears.

3. The combination of sign rollers and a flexible sign mounted thereon; of gears mounted upon the shafts of said rollers; driving gears adapted to respectively engage said first mentioned gears; an operating

shaft on which said driving gears are loosely mounted; hubs formed on said driving gears and having oppositely disposed clutching recesses, said operating shaft having a longitudinal groove formed therein; a pawl pivoted intermediate its ends in the groove in said operating shaft, and having its free ends coöperating respectively with the clutching recesses in the hubs of the driving gears.

10 4. The combination of sign rollers and a flexible sign mounted thereon; of gears mounted upon the shafts of said rollers; driving gears adapted to respectively engage said first mentioned gears; an operating shaft on which said driving gears are loosely mounted; hubs formed on said driving gears and having oppositely disposed clutching recesses, said operating shaft having a longitudinal groove formed therein; a pawl pivoted intermediate its ends in the groove in said operating shaft and having its free ends coöperating respectively with the clutching recesses in the hubs of the driving gears, said pawl being shaped so that when 15 one end thereof is in engagement with one driving gear, the other end thereof is out of engagement with the other driving gear.

20 5. The combination with sign rollers and a flexible sign mounted thereon; gears mounted upon the shafts of said rollers;

driving gears adapted to respectively engage said first mentioned gears; hubs carried by said driving gears; a driving shaft on which said hubs are loosely mounted, each of said hubs having a clutching recess formed with 35 a radial shoulder and a curved surface leading therefrom, said operating shaft having a longitudinal groove formed therein; a pawl pivoted intermediate its ends in the groove in said operating shaft, the free ends 40 of said pawl adapted to coöperate with the clutching recesses formed in the hub, and said pawl being shaped so that when one end thereof engages one recess, the other end thereof is held out of engagement with the 45 other recess, and the clutching recesses in the driving hubs being arranged in opposition to one another, whereby when the operating shaft is rotated in one direction, one of the driving gears is connected therewith, and when rotated in the opposite direction the other driving gear is connected therewith.

In testimony whereof, I have hereunto signed my name, at Philadelphia, Pennsylvania, this fourteenth day of July, 1910.

CHARLES E. BONINE.
